UNITED STATES PATENT OFFICE.

CHARLES A. JUENGST, OF CROTON FALLS, NEW YORK, ASSIGNOR TO AMERICAN ASSEMBLING MACHINE COMPANY, INC., OF MEMPHIS, TENNESSEE, A CORPORATION OF DELAWARE.

BOOK COVERING AND BINDING MACHINE.

1,389,762.

Specification of Letters Patent. Patented Sept. 6, 1921.

Application filed November 11, 1919. Serial No. 337,159.

To all whom it may concern:

Be it known that I, CHARLES A. JUENGST, a citizen of the United States, and a resident of Croton Falls, in the county of Westchester and State of New York, have invented certain new and useful Improvements in Book Covering and Binding Machines.

The present invention relates to book covering binding machines or machines that perform both of these functions and has for its main object the provision of means whereby books of widely different makeup may be bound or covered or both.

In the accompanying drawings the invention is embodied in a concrete and preferred form in which—

Figure 1 is a more or less diagrammatic view chiefly in side elevation of a portion of a machine embodying the invention:

Fig. 2 is a rear elevation, partly broken away, of the devices for feeding crash and cardboard to the book:

Fig. 3 is a view in end elevation looking in the direction of arrow 3 of Fig. 2, part of the main frame of the machine being shown in section:

Fig. 4 is a detail view in elevation of the cover feeding and gluing means:

Fig. 5 is a broken view in elevation looking in the direction of the arrow 5 of Fig. 4:

Fig. 6 is a detail sectional view on the line 6—6 of Fig. 2:

Fig. 7 is a detail sectional view on the line 7—7 of Fig. 5: and

Fig. 8 is a sectional view showing one style of book produced by the machine.

Although the machine of the invention is adapted to act purely as a covering machine for, say, stitched or stapled books, the product that it is more particularly desired to obtain is shown in Fig. 8. As there disclosed, the signature group 1 is trimmed at the bottom or back, glue is applied and a strip 2 of crash, or the like, and a blank 3 of cardboard, or the like, are pressed against the glued back, the crash being between the back of the signature group and the cardboard. A cover 4 is then glued on the cardboard blank after which the cover is broken.

As shown in Fig. 1, the machine as a whole may consist of a book conveyer 5 traveling in a horizontal orbit and having clamps 6. The construction of the conveyer and the various instrumentalities that act on the

book, except those hereafter explained in detail, may be the same or substantially the same as those shown in Patents Nos. 1,193,395 and 1,244,861. Preferably the book conveyer has a continuous advancing movement. Arranged along the path of the book conveyer are the various instrumentalities that act on the book here taking the form of a cutting mechanism 7 for cutting off the back of the book, a roughening device 8 for rendering the back of the book more receptive to glue, a glue applying means 9, a crash and cardboard feed 10, covering feeding means 11, glue applying means 12 and a cover breaker 13.

As in the machines of Patents Nos. 1,193,395 and 1,244,861 it is desired to perform all the binding or covering operations, or both, while the book is on the run although the features of the invention are not necessarily limited to a so-called "continuous" machine.

In the production of a book such as is shown in Fig. 8, the signature group is trimmed and roughened and glue is applied to the back of the book. The crash and cardboard are now applied to the book, and the means for accomplishing it as here disclosed take the following form. 14 is a hopper for cardboard blanks 3, and these blanks are delivered singly from the bottom of the hopper as by means of a slide 15 actuated by means of lever 16, pivoted at 17, rod 18, cam lever 19, pivoted at 20, having cam roll 21 engaging cam 22.

23 is a cradle or frame consisting of side cheeks 24 connected by means of member 25, the latter being mounted on two cranks 26 rotated by means of shafts 27 that receive motion in some suitable way, as by means of sprocket wheels 79. Mounted on member 25 is a presser element 28 of a length equal to that of the back of the longest book that the machine is adapted to act upon. The lower ends of cheeks 24 constitute means for supporting a source of supply 29 of crash in web form. Cheeks 24 also carry a guide roller 30 and a feed cylinder 31, the latter of which may consist of a number of pulleys mounted on shaft 32. Coacting with cylinder 31 is a pressure roller 33. Cylinder 31 is rotated intermittently by means of pawl 34 and ratchet 35, said pawl being hung loosely on shaft 32 by means of

arm 36 which is pivotally connected to link 37 connected in turn to crank 38 on shaft 39. Shaft 39 is supported in bracket 40 carried by member 25 and is driven by means of 5 worm gears 41 and 42. Gear 42 is fixed to the crank pin 26 and by its revolution drives gear 41. Adjacent the upper side of cylinder 31 are suitable guides 48 mounted between the pulleys comprising said cylinder, 10 and in close proximity to the guides and cylinder are two knives 49 and 50 arranged substantially at right angles to each other. Knife 49 is relatively stationary but knife 50 is mounted in holder 51 pivoted at 52 and 15 normally held out of contact with 49 by means of spring 53. Both knives are carried by the cradle. Holder 51 has an abutment surface 54 (Fig. 3) which, when brought in contact with stationary cam 55 20 in the main frame of the machine, acts to depress knife 50 and to sever a section from the crash web.

The revolution of cranks 26 raises and lowers the cradle and also moves it longitudinally substantially in unison with the book conveyer when the cranks are passing through their upper arc of movement, the cradle carrying with it presser element 28 and the source of supply of crash as well as 30 the crash feeding and severing elements. When presser element 28 reaches the level of slide 15 on its up stroke, a cardboard blank 3 is deposited on said presser element. After the blank is deposited on the presser 35 element, pawl 34 and ratchet 35 feed a section of the web on top of the blank, this occurring during the continued upward and forward movement of the cradle. Eventually, abutment surface 54 strikes cam 55 and 40 the section is severed from the web and the continued upward and forward movement then presses the crash and blank against the glued back of the book. After this, the cradle returns and the operation is repeated 45 on the next book.

A cover is next applied to the book and this is accomplished by means of cover feeding means 11 and cover breaker 13. The cover feeding means here comprise chains 50 56, carrying the cover over supporting guides 57, and cover drum 58. This cover drum may or may not roll the sheet against the back of the book as explained in Patent No. 1,193,395. In the form here disclosed 55 the cover sheet is received in the bite of drum 58 and tapes 59, the latter passing over pulleys 60. Chains 56 run in grooves below the surface of drum 58 as explained in said Patent No. 1,193,395 so as not to interfere 60 with the control of the cover sheet by drum 58 and tapes 59. Adjacent the cover drum is a glue pot 61 having a glue roller 62 rotatably mounted on shaft 63. This shaft is carried in arms 64 of rockshaft 65 and 65 springs 66, acting on the free end of arms

64, normally urge glue roller 62 toward cover drum 58. A cam 67 rotating with cover drum shaft 68, acts against roller 69, carried by arm 70 on rockshaft 65, to move glue roller 62 away from cover drum 58 in 70 the interval between successive sheets. 71 is a detector consisting of a plurality of fingers extending into grooves 72 of cover drum 58 and mounted on shaft 72a having at its other end abutment member 73. When a sheet passes to the cover drum at the proper time, it will move detector fingers 71 out of grooves 72 and abutment member 73 will be out of the path of heel 74 of arm 64 and spring 66 will, therefore, be free to lift the glue roller into contact with the sheet carrying cover drum. If, however, no cover sheet is present at the proper time, spring 75 will retain detector 71 in grooves 72 and abutment member 73 will be in the path of heel 74 and spring 66 will be unable to lift the glue roller. 75 (see Fig. 7) is a scraper 80 acting against glue roller 62 and mounted on arm 76 pivoted at 77 in the bearings of shaft 63. Arm 76 carries an adjusting screw 78 that comes against the stop formed by shaft 65. By this means, the thickness of 85 the layer of glue on the glue wheel is controlled.

The cover sheet arriving at the cover drum is glued in the center and is then pressed into contact with the cardboard blank on the back of the book. As previously explained, the cover pressing may be performed by the cover drum. After this 90 the cover is broken by cover breaker 13.

In some shops, the character of the make-up of the books varies. For instance, when stitched books are run through the machine, the binding means are rendered inoperative. 105 Thus, in the machine of the present application, the instrumentalities 7, 8, 9 and 10 may be rendered inoperative and the machine may then be run as a coverer by means of the instrumentalities 11, 12 and 13. 110

I claim:

1. A binding and covering machine comprising: a book conveyer including a plurality of clamps for supporting books in an upright position, and binding and covering means located adjacent to the path of the book conveyer including: means for gluing a strip of crash and a cardboard blank to the back of the book with the crash intermediate the book and cardboard, means for gluing a cover to the cardboard blank on the back of the book, and cover breaking means.

2. A binding and covering machine comprising: a book conveyer including a plurality of clamps for supporting books in an upright position, and binding and covering means located adjacent to the path of the book conveyer including: means for applying glue to the back of the book, means for 120

position and having a continuously advancing movement in a horizontal orbit, and binding means located adjacent to the path of the book conveyer including: means for applying adhesive to the back of books, a relatively stationary hopper for cardboard blanks, means for feeding a cardboard blank from the hopper, a cradle, means for lifting and lowering the cradle with respect to the hopper and book conveyer and for imparting to said cradle an advancing movement substantially in unison with the conveyer when the cradle is on its upstroke, a presser element carried by the cradle for receiving a blank from the hopper as it moves past it in an upward direction, a source of supply of crash in web form moving with the cradle, means, moving with the cradle, for feeding a section of the web into superposed position on the cardboard blank on the presser element, and means for severing the superposed section of crash from the web.

11. A binding machine comprising: a book conveyer including a plurality of clamps for supporting books in an upright position and having a continuously advancing movement in a horizontal orbit, and binding means located adjacent to the path of the book conveyer including: means for applying adhesive to the back of books, a relatively stationary hopper for cardboard blanks, means for feeding a cardboard blank from the hopper, a cradle, a pair of horizontally disposed rotating cranks supporting said cradle, a presser element carried by the cradle for receiving a blank from the hopper as it moves past it in an upward direction, a source of supply of crash in web form moving with the cradle, means, moving with the cradle, for feeding a section of the web into superposed position on the cardboard blank on the presser element, and means for severing the superposed section of crash from the web.

12. A binding machine comprising: a book conveyer including a plurality of clamps for supporting books in an upright position and having a continuously advancing movement in a horizontal orbit, and binding

means located adjacent to the path of the book conveyer including: means for applying adhesive to the back of books, a relatively stationary hopper for cardboard blanks, means for feeding a cardboard blank from the hopper, a cradle, means for lifting and lowering the cradle with respect to the hopper and book conveyer and for imparting to said cradle an advancing movement substantially in unison with the conveyer when the cradle is on its upstroke, a presser element carried by the cradle for receiving a blank from the hopper as it moves past it in an upward direction, a source of supply of crash in web form moving with the cradle, means, moving with the cradle, for feeding a section of the web into superposed position on the cardboard blank on the presser element, and means for severing the superposed section of crash from the web.

13. In a covering machine, a cover drum, a glue roller adjacent the cover drum, means for moving the glue roller toward and away from the cover drum, means for detecting the absence of a cover sheet on the drum, and means for preventing the glue roller from moving toward the drum when a cover is missing.

14. A binding mechanism comprising: a book conveyer including a plurality of clamps for supporting books in an upright position, and book binding means located adjacent to the path of the clamps including: a crash and card-board feeding mechanism, a cover feeding mechanism and two glue applying mechanisms, one located in advance of the crash and card-board feeding mechanism to apply glue to the books in the clamps, and the other intermediate the crash and card-board feeding mechanism and the cover-feeding mechanism to apply glue to the covers before they reach the books in the clamps.

Signed at Croton Falls, in the county of Westchester and State of New York, this 27th day of October, 1919.

CHARLES A. JUENGST.
